Des. 204,449

Patented Apr. 19, 1966

204,449

PAINTER'S BRUSH OR THE LIKE

Rudolf Zavodsky, 27 Sudtirolerstrasse, Maria-Enzersdorf, near Vienna, Austria

Filed Mar. 1, 1965, Ser. No. 84,001

Claims priority, application Austria Sept. 1, 1964

Term of patent 7 years

(Cl. D9—2)

I claim:

The ornamental design for a painter's brush or the like, as shown.
